CLAIM

We claim the ornamental design of a sandal, as shown and described.

DESCRIPTION

FIG. 1 is a perspective view of a sandal, in accordance with the design;

FIG. 2 is a perspective view of the sandal;

FIG. 3 is a view of a first side of the sandal;

FIG. 4 is a view of a second side of the sandal, opposite the first side;

FIG. 5 is a top view of the sandal;

FIG. 6 is a bottom view of the sandal;

FIG. 7 is a front view of the sandal; and,

FIG. 8 is a rear view of the sandal.

The broken lines in the figures illustrate boundaries that form no part of the design to be patented.
